UNITED STATES PATENT OFFICE.

WALTER O. LUM, OF NEW YORK, N. Y., ASSIGNOR TO BLO-DRY INCORPORATED, OF SYRACUSE, NEW YORK, A CORPORATION OF NEW YORK.

NOZZLE FOR ELECTRIC DRIERS.

Application filed December 2, 1924. Serial No. 753,471.

My invention relates to improvements in construction of nozzles, nozzle guards, and nozzle heater units for electric drying devices. The chief objects of my invention are to create a nozzle for an electric drier which will develop the highest possible mechanical efficiency.

The further object in my invention is to design an electric heater grid unit, of the type which is ordinarily to be inserted in these nozzles, of such construction and mounting that it will provide minimum obstruction in the air passage; that it will contain the greatest possible length of resistor material in the minimum space; that it will be rugged and fireproof, easy to remove and renew or replace; and be simple in construction.

The further object of my invention is to provide a demountable resistor unit which can be readily positioned in fuse clips and by which I am able to adapt my motor for any voltage. That is to say, that by carrying certain standard windings of resistor units and placing them in the readily adapted fuse clips I may use the same motor on any line voltages encountered and I prefer to mount this variable resistor unit in connection with the general mounting of my nozzle.

The further object of my invention is to provide a nozzle of this type equipped with a suitable guard mounting so that it will not be possible to clog the outlet end of the nozzle by the hands or other objects such as books and also to prevent the nozzle from being easily obstructed by paper wads or rags, and at the same time construct the nozzle guard in such manner that the air stream will not be obstructed; that the guard shall be simple but rugged in design and easily and permanently attached to the nozzle proper without screws.

In order that my invention may be more fully understood reference will now be made to the accompanying drawings in the various figures of which like letters refer to like parts.

Figure 1 is a diagrammatic wiring diagram showing the electrical wiring in a conventional hot air drier.

Figure 2 is a plan view of the grid resistor unit portion of my device.

Figure 3 is a front elevation of the grid resistor unit portion of my device.

Figure 4 is an end elevation of the grid resistor unit portion of my device.

Figure 5 is an elevation of a section of a typical hot air drying device showing the positioning of my nozzle guard and heat resistor units, a portion of the same being a sectional illustration.

In the drawings similar letters of reference denote similar parts in the several views. Referring to Figure 1 the motor armature D is shown connected to the field E. I show my motor resistor unit at C. The ohmic resistance of this unit is varied, depending on the line voltage which is encountered in any particular case and I prefer to make these resistance units in such manner that they may be mounted in fuse clips shown in Figure 5 at CC. The fuse clip block BB in Figure 5 being connected to the nozzle by the screws DD. In Figure 1, at B, is shown diagrammatically the connections of my heating element and the whole circuit is closed by means of the switch A. Referring to the heater unit in Figure 2, I show a plan view of this unit. The terminals K, G are connected when the unit is in place with stationary conductors mounted on the suitable portion of my nozzle proper. The sides J and H of the heater unit slide into the notches or grooves or slots designated Z in Figure 5, so that they may be readily removable and these side portions J and H are connected together by the strip L composed of fibre, mica or other insulating material.

It must be understood that while in my drawings I only show four mica sections I—I any number of such sections may be used. I also prefer that each end of my mica sections are notched so that they register with corresponding notches in the top and bottom cross supports L. In some cases the side supports in addition to carrying the ordinary terminals K—G also carry an extra terminal for connecting the heat resistor unit to the motor. This I do in cases where the motor operates at lower voltage than the main supply currents and supplements the motor resistor unit. For example, if the motors are wound standard for 110 volts and it is intended to operate a blower on a 220 volt line, the third terminal on the heat resistor unit is placed midway of the wiring thus giving approximately 110 volts to the motor.

The individual segments I—I of the resistor unit are composed of sections of thin mica upon which the resistance B is wound and are held together by rivets P and are 5 notched on the edges at N to take the resistor wires. These sections are then held together by fitting into the cross piece L in the notches provided in the top portion M and the entire frame is held together by small 10 rivets Q and the cross sections L are additionally strengthened by combined rivets and conductor studs R, the various sections being electrically connected and the end portions having an outlet O to provide a connection to the terminals G and K.

Referring to Figure 5, a preferred embodiment shows the top of my nozzle case at T with a nozzle guard S. The nozzle guard S is preferably composed of six radial pieces, 20 shaped as shown, clamped on to the top portion T coming down in the center to a central piece to give rigidity. It will be seen that if any obstructing material is placed in the top of the nozzle, such as a book or hand, 25 they cannot completely close the same on account of the shape of my nozzle guards.

At U is shown the inside of the nozzle and on account of the rough undersurface I provide an inner inverted funnel or nozzle 30 cone or inner nozzle V which centralizes and directs the air stream and enables me to affect a change in the size of the outlet not otherwise changing the permanent parts of the blower. I also provide the screen W to prevent 35 small pieces of foreign matter from falling directly into the device. This screen or grid guard is mounted directly over the heater unit as far from the outside opening as possible. The grid guard is constructed 40 of thin edgewise strips rather than round wire because of the less resistance offered by such a strip to the air stream. The strips are all notched the same, half way through and when assembled make a very rugged 45 unit.

At X is the end of the blower casting proper and Y shows spaces which are provided in the outer cover of a typical blower 50 device forming a seal for the blower. E E forms the center line of the blower and F F is the bottom of the blower casting while

A A is the outer frame of a typical blower device. It will now be seen that by removing the outer case A A I can very readily dis-assemble the nozzle, motor resistor and heat resistor units and it will also be seen that the construction of the heat resistor unit and its position in the nozzle is so arranged that the air stream has the least possible obstruction.

While I have disclosed one preferred embodiment of my invention, it must be understood that other possible arrangements are within the scope of my invention and claims.

Having thus described my invention what I claim and desire to secure by United States Letters Patent is:

1. In a nozzle for electric driers the combination of a top guard on the outer end of said nozzle with an outer closure case, an inner nozzle cone, a screen grid guard, an electric heating unit adapted to be mounted in the nozzle of such driers and consisting of two insulating side support members, two cross supporting members, a plurality of intermediate members wound with resistor wire, said insulating side support members provided with terminals and all adapted to be slidably mounted in a vertical manner in the nozzle passage of said drying device, all as and for the purposes hereinbefore set forth.

2. In a nozzle for electric driers the combination of a top guard for the outer end of said nozzle with an outer closure case, an inner nozzle cone, a screen grid guard, an electric heating unit adapted to be mounted in the nozzle of such driers and consisting of two insulating side support members, two cross supporting members, a plurality of intermediate members wound with resistor wire coils, said insulating side supporting members provided with terminals and all adapted to be slidably mounted in a vertical manner in the nozzle passage of said drying device, said unit also provided with an electrical motor connecting terminal tap intermediate its length.

In witness whereof I have hereto signed my name this 19th day of September, 1924.

WALTER O. LUM.
